UNITED STATES PATENT OFFICE.

MELVIN S. GREELEY, OF DES MOINES, IOWA.

GRAIN-DOOR.

1,013,766.

Specification of Letters Patent.

Patented Jan. 2, 1912.

Application filed August 7, 1911. Serial No. 642,616.

To all whom it may concern:

Be it known that I, MELVIN S. GREELEY, a citizen of the United States, residing at Des Moines, in the county of Polk and State of Iowa, have invented a new and useful Grain-Door, of which the following is a specification.

This invention relates to grain doors, and particularly to grain doors adapted for use 10 on box cars.

The object of this invention is to produce a door of this character which can be conveniently and readily arranged in operative position or removed therefrom.

15 This invention embodies a novel construction, combination and arrangement of parts, and is embodied principally in a plurality of door sections arranged to set one on the other in the doorway and be removed therefrom to slide along the side of the wall when brought to a raised position, as will be evident from the hereinafter description.

20 This invention is illustrated in the accompanying drawings, in which similar reference characters indicate similar parts, and in which—

25 Figure 1 is an exterior elevation of a side wall of a car embodying the invention. Fig. 2 is an interior elevation thereof. Fig. 3 is a vertical section taken through the doorway, being on an enlarged scale. Fig. 4 is a horizontal section in detail taken through one side of the door frame, with parts broken away.

30 Referring specifically to the drawings, 6 designates the side wall of a box car or the like having the usual doorway 7. A sliding door 8 is mounted on the dove-tail shaped tracks 9 at the top and bottom of the wall 6 to slide over the doorway and away therefrom. The tracks 9 are preferably spaced slightly from the sides of the car to prevent sleet and snow from collecting thereon, and the door 8 is provided with a latch 10 for 35 locking same when closed. This sliding door 8 forms an outer door for a doorway which is used in connection with the inner or grain door, as will be hereinafter described.

40 The door posts 26 on each side of the doorway each has an inner rabbet 25 and to these posts 26 are secured the inner linings 11 at the sides of the doorway, which linings extend from the floor upward to a position below the top of the doorway. The strips 12 are secured to the edges of the linings 11 and

project beyond the edges thereof to form a channel 30 between each of the strips 12 and the corresponding rabbet of the door post at each side of the doorway. The upper 40 ends of the strips 12 are deflected inwardly or offset as indicated at 12^a, the upper extremities being secured to the wall of the car above the doorway. A track 18 is secured to the inner side of the wall 6 at each 45 side of the doorway above the linings 11, each of the said tracks comprising a channel of dove-tailed shape. These tracks 18 are preferably declined slightly from the doorway and the inner extremities thereof 50 pass in under the portions 12^a of the strips 12 to the edges of the doorway. At the top of the doorway and on the inner side thereof are secured a pair of angular members 16 having one of the flanges thereof spaced inwardly from the side wall of the car and projecting upward to form a track. The inner extremities of the said members are 55 spaced apart and the outer extremities thereof extend in under the deflected portions 12^a of the guide strips 12.

55 The grain door sections are designated at 13, each having a hooked member 14 secured centrally of the upper end thereof, a dove-tailed rib 21 extending horizontally across 60 the front side thereof, and a lip 15 secured to the lower edge thereof on the inner face. These door sections 13 are arranged to set one on the other in the doorway with the extremities thereof extending into the channel formed between the rabbets 25 of the door posts 26 and the guide strips 12. The lips 15 of the upper sections overlap the upper edges of the lower sections to close 65 the crevice between the sections, and the lip 15 of the lower section overlaps the foot board 23 at the bottom of the doorway. The upper sections are also provided with recesses 24 on the lower edge thereof into 70 which the hooks 14 of the lower sections project when the sections are set upon each other. The lowermost section of the grain door is provided with a small door 19 hinged thereto to swing outwardly and being adapted to be locked against being 75 opened by the latch 20 mounted on the said section and the member 22 carried by the said door 19. This door 19 being on the lower section can readily be opened when desired to let the grain escape from the car 80 therethrough.

85 In use, the door sections 13 are removed

from the doorway by raising same to the top of the doorway which permits the hooks 14 thereof to pass between the space between the tracks 16 and bring the ribs 21 of the door sections in alinement with the tracks 18, and then by pushing the said sections to either side of the doorway the ribs 21 enter the channel tracks 18 allowing the sections to be slid along the inner wall of the car. It will be noted that upon being slid to either side, the hooks 14 and the ribs 21 simultaneously engage the respective tracks 16 and 18 which prevent the said sections from being removed from the car, the hooks 14 engaging the tracks 16 guide the door sections until they are safely held in position by the tracks 18. To bring the door sections in operative position the same are moved toward the doorway, the hooks 14 thereof sliding over the tracks 16 until the said hooks come between the inner ends of the tracks 16 when the door section can be lowered into the doorway between the guideways and the sides thereof. In this manner the respective door sections can be readily brought in operative position in the doorway and be removed therefrom. When the grain door sections are in operative position and after the car has been filled with grain, the outer door 8 is closed which forms an additional closure for the doorway. The tracks 18 being declined from the doorway prevents the door sections from sliding therefrom due to the jolting action to which the car is susceptible and retains the door sections thereon until manually slid therefrom to be brought in position in the doorway.

It will be understood that this grain door can be built from lumber, sheet steel or other material and that the same is susceptible of alteration in its details within the scope of the appended claims without departing from the spirit of the invention.

45 What is claimed is:

1. The combination with a wall having a doorway therein and guide-ways at the sides

of the door-way, of a track secured to the side wall at each side of the door-way, a pair of tracks secured at the top of the door-way having their inner extremities spaced from each other, a plurality of door sections adapted to set one on the other in the said door-way between the guide-ways, a hook secured to each door section adapted to pass between the extremities of the tracks at the top of the door-way and engage the said tracks upon the door sections being slid to one side, and a track engaging member carried by each door section and adapted to engage the tracks at the sides of the doorway upon the door sections being slid sidewardly.

2. The combination with a wall having a doorway therein, and guide strips secured at the sides of the doorway having upper deflected portions, of a pair of tracks secured to the said wall at each side of the doorway having their inner extremities arranged within the said deflected portions of the guide strips, a pair of tracks secured at the top of the doorway having their inner extremities spaced from each other and having their outer extremities projecting in under the said deflected portions of the strips, a plurality of door-sections adapted to set one on the other in the said doorway between the guideways, a hook secured to each door section adapted to pass between the extremities of the tracks at the top of the doorway and engage the said tracks upon the door section being slid to one side, and a track engaging member carried by each door section adapted to engage the tracks at the sides of the doorway upon the door section being slid sidewardly, for the purpose described.

In testimony that I claim the foregoing as my own, I have hereto affixed my signature in the presence of two witnesses.

MELVIN S. GREELEY.
